US0D1070134S

(12) **United States Design Patent** (10) **Patent No.:** **US D1,070,134 S**
(45) **Date of Patent:** **** Apr. 8, 2025**

(54) **VEHICLE HEADLIGHT**

(71) Applicant: **Polestar Performance AB**, Gothenburg (SE)

(72) Inventor: **Markus Offen**, Gothenburg (SE)

(73) Assignee: **Polestar Performance AB**, Gothenburg (SE)

(**) Term: **15 Years**

(21) Appl. No.: **29/826,612**

(22) Filed: **Feb. 14, 2022**

(51) LOC (15) Cl. **26-06**

(52) U.S. Cl.

USPC **D26/28**

(58) **Field of Classification Search**

(57) **CLAIM**

The ornamental design for a vehicle headlight as shown.

DESCRIPTION

FIG. 1 is a right front perspective view of a vehicle headlight showing the claimed design;

FIG. 2 is a right rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
